SLIPPER BEARING

Joseph P. Ruth, Denver, Colo.

Application May 11, 1935, Serial No. 21,018

10 Claims. (Cl. 105—82)

This invention relates to improvements in slipper bearings, and more particularly to such bearings as employed in railway locomotives, cars, and the like.

5 In railway locomotive and car construction it is customary to support the frame of the unit on springs that are connected by means of equalizing levers, which, in turn, rest on the axle bearing. In order to prevent undue strains the equalizing levers are supported on arcuate bearing surfaces that permit the levers to rock to a limited extent.

10 Where railway units travel over tracks that are quite crooked, as is often the case in narrow gauge tracks constructed in mountainous countries, the axles must be so connected with the rigid frame that they will have considerable movement transversely of the car so as to adapt themselves to the curvature of the track.

15 It is the object of this invention to produce a slipper bearing that shall be especially well adapted for use with railway units that travel over crooked and uneven railway tracks and which, in addition to the usual rocking movement, shall 20 also be so constructed that the parts can slide relative to the axle housing so as to permit the wheels to properly adjust themselves to the rails without imposing undue strains on the bearings.

25 This invention, briefly described, comprises a bottom block that is adapted to rest on the upper surface of an axle housing and which has its top provided with a concave cylindrical surface having an axis of curvature extending in the direction of the length of the axle housing.

30 Supported on the bottom block is a second block having an under surface formed from a convex cylindrical surface of the same curvature as that of the concave surface in the bottom block. The upper surface of the second block is 35 provided with a concave cylindrical surface the axis whereof is perpendicular to the axis of the convex under surface. The spring supporting and equalizing levers, which are usually bowed, are provided on their under surfaces with downwardly extending projections having lower ends formed with convex cylindrical surfaces that fit the concave cylindrical surfaces in the tops of the second blocks. This construction permits the second block to rock on the bottom block and also 40 slide in respect thereto and at the same time permits the spring supporting levers to rock and slide with respect to the second block.

45 Having thus briefly described the invention, the same will now be described in detail, and for this purpose reference will be had to the accom-

panying drawing in which the preferred embodiment of the invention has been illustrated, and in which:

Fig. 1 is a side elevation, partly in section, of the side of a railway truck showing the position 5 of the slipper bearings;

Fig. 2 is a section taken on line 2—2, Fig. 1; and

Fig. 3 is a section taken on line 3—3, Fig. 2.

10 In the drawing reference numeral 4 indicates the axle of a railway car truck to the ends of 15 which the wheels 5 are connected. The wheels are of usual construction and form no part of this invention and have therefore been shown in a diagrammatic manner. The axles are mounted for rotation in an axle housing which has been designated by reference numeral 6. This axle housing is also of the usual construction and is provided at each end with a substantially rectangular portion 7 that is located for reciprocation between the guides 8. The lower ends of the guides 20 are connected by a frame member 9, while the upper ends thereof are attached to or connected with a frame member 10. The weight of the car body and its load rest on the frame member 10 and the latter is provided at spaced intervals 25 with downwardly-extending posts 11 that rest on the springs 12. The ends of the springs are connected by means of stirrups 13 with the ends of spring supporting and equalizing levers 14. The levers 14 are preferably bowed and positioned with 30 their convex sides upwardly. The upper surface of each lever is provided with a recess 15 like that shown in Fig. 2 and these recesses serve to receive the frame members 10. Each of the spring supporting levers is provided on its lower side with 35 a downwardly-extending projection 16 terminating in a convex cylindrical surface 17. Resting on the top of the rectangular portion 7 at each end of the axle housing is a bottom supporting block 18. The top of this block is provided with 40 a concave cylindrical surface 19 having an axis of curvature extending in the direction of the length of the axle housing. The bottom supporting block has its base portion extended outwardly a short distance, as designated by reference 45 numeral 20, and extended upwardly from the portion 20 are vertical walls 21 that form with the portion 20 and the sides of the block a rectangular channel for the reception of oil or grease. Supported on the bottom block is a second block 50 which has been designated by reference numeral 22 and which has an under portion formed by a cylindrical surface of the same curvature as the concave cylindrical surface in the bottom block 18. The top of the second block is provided with 55

5 a concave cylindrical surface 23 having an axis of curvature perpendicular to the axis of curvature of the convex bottom surface. The radius of curvature of the concave cylindrical surface in the 10 top of block 22 is the same as that of the convex cylindrical surface 17 at the lower end of the projection 16. A cover 24 is applied to the walls 21 and is provided at its center with an opening surrounded by the vertical wall 25. The spring 15 supporting levers are provided with downwardly extending flanges 26 that surround the projections 16 and the vertical wall 25.

When the parts above described are assembled, they form an assembly like that shown in Fig. 1 15 and in greater detail in Figs. 2 and 3.

It will be apparent that since the frame is rigid and since it is necessary in going around steep curves for the wheels to move transversely with respect to the frame, the bottom block 18 20 that is secured to the axle housing will move with respect to the block 22 and this motion is permitted by the two cylindrical bearing surfaces having axes of curvature extending in the direction of the length of the axle housing. If one 25 axle moves vertically with respect to the adjacent axle, this produces a rocking action of the spring supporting and equalizing levers 14. Since these levers rest on the second block 22, this rocking action will cause the block 22 to rock with respect to the block 18 about the axis of the cylindrical bearing surfaces. If one side of the truck moves downwardly or upwardly with respect to the other side, this will produce a rocking motion 30 between the surfaces 17 and 23.

35 It will be seen from the above that when railway units are provided with slipper bearings like those illustrated on the drawing and described herein, the axle housings can move freely with respect to the frame without producing any severe 40 strains because the universal movement provided by the slipper bearing described permits any and all adjustments to be automatically effected without strain.

Particular attention is called to the fact that 45 the axle housing can move transversely with respect to the frame due to the sliding action permitted between the two cylindrical surfaces on the bottom block and block 22.

Attention is also directed to the fact that the 50 cylindrical surfaces 17 can slide with respect to the block 22 and also rock with respect thereto, and in this way practically every conceivable adjustment can take place without producing severe strains on any part. By filling the chamber between the walls 21 with oil or grease, the parts 55 will always remain properly lubricated and the flange 26 and wall 25 serve as means to prevent dust and dirt from entering the chamber where the bearings are located.

60 It is, of course, possible to turn the several cylindrical bearing surfaces through an angle of ninety degrees and get approximately the same effects and such a construction is considered to be a mechanical equivalent of the one illustrated, 65 described and claimed.

I claim as my invention—

1. A slipper bearing comprising a cylindrically concaved seat, a weight-supporting shoe formed with a cylindrically convexed bearing surface depending for operative association with said seat, and a bearing block interposed in freely floating, self-positioning relation between and contoured for both linearly and angularly movable cooperation with said seat and shoe. 70

75 2. A slipper bearing comprising a cylindrically

concaved seat, a weight-supporting shoe formed with a cylindrically convexed bearing surface depending for operative association with said seat, the cylindrical axes of said seat and shoe being perpendicularly related, and a bearing block interposed in freely floating, self-positioning relation between and contoured for both linearly and angularly movable cooperation with said seat and shoe. 5

3. In a truck, a slipper bearing comprising a 10 cylindrically concaved seat, a weight-supporting shoe formed with a cylindrically convexed bearing surface depending for operative association with said seat, a bearing block interposed in freely floating, self-positioning relation between 15 and contoured for both linearly and angularly movable cooperation with said seat and shoe, wheeled means supporting said seat, and a frame resiliently carried by said shoe. 15

4. A slipper bearing comprising a seat formed 20 with an upwardly-opening, cylindrically-concaved bearing zone, a weight-supporting shoe formed with a cylindrically convexed bearing surface depending in spaced, axially-perpendicular relation with the bearing zone of said seat, a 25 bearing block interposed in freely floating, self-positioning relation between and cooperatively associating said seat and shoe, and cylindrically contoured areas on said bearing block for linearly and angularly movable bearing cooperation with 30 the contoured surfaces of and for retention of said block between said seat and shoe.

5. A slipper bearing comprising a seat formed with an upwardly-opening, cylindrically-concaved bearing zone, a bearing block formed with 35 a cylindrical under portion freely floating within and cooperating for relative linear and angular motion with the bearing zone of said seat, a cylindrically-concaved bearing zone formed on said block in vertically-spaced, axially-perpendicular 40 relation with the bearing zone of said seat, and a weight-supporting shoe depending to a cylindrically-convexed bearing surface seated in floating relation in and cooperating for relative linear 45 and angular motion with the bearing zone of said block, whereby said block is mounted to float in self-positioning relation and for accommodation of relative displacement between said seat and shoe. 45

6. In a truck, a slipper bearing comprising a 50 seat formed with an upwardly-opening, cylindrically-concaved bearing zone, wheeled means supporting said seat, a bearing block formed with a cylindrical under portion engaging within and cooperating for relative linear and angular motion 55 with the bearing zone of said seat, a cylindrically-concaved bearing zone formed on said block in vertically-spaced, axially-perpendicular relation with the bearing zone of said seat, a weight-supporting shoe depending to a cylindrically-convexed bearing surface seated in and cooperating for relative linear and angular motion 60 with the bearing zone of said block, and a frame resiliently associated with said shoe. 60

7. The combination with a wheeled support and a rigid frame carried by and for limited motion 65 relative to said wheeled support, of a slipper bearing operatively associating said frame and wheeled support, said bearing comprising a seat in fixed relation with said wheeled support, a 70 bearing block engaging and cooperating for relative linear and angular motion with said seat, a weight-supporting shoe engaging and cooperating with said block for relative linear and angular motion in paths perpendicular to those of the 75

travel between said seat and block, and means resiliently interconnecting said shoe and rigid frame; together with guide means operatively engaging between said wheeled support and rigid frame.

5 8. A slipper bearing comprising a seat, a bearing block engaging and cooperating for relative linear and angular motion with said seat, a weight-supporting shoe engaging and cooperating with said block for relative linear and angular motion in paths perpendicular to those of the travel between said seat and block, and housing elements in fixed relation with said seat and shoe, respectively, cooperating in relatively shiftable relation to enclose said bearing assembly.

10 9. A slipper bearing comprising a seat, a bearing block engaging and cooperating for relative linear and angular motion with said seat, a weight-supporting shoe engaging and cooperating with said block for relative linear and angular motion in paths perpendicular to those of the travel between said seat and block, a housing element in fixed relation with and surrounding said seat and formed with an upstanding flange surrounding and spaced from said shoe, and a housing element in fixed relation with said shoe and formed with a depending flange cooperating in

relative shiftable telescoping relation with said upstanding flange to complete an enclosure for said bearing assembly.

15 10. In a slipper bearing having a fixed bearing seat, a bearing block shiftably cooperating with said seat and a weight-supporting shoe shiftably engaging said block, a base in fixed relation with and extending marginally beyond said seat, a wall rising from margins of said base in surrounding relation with the bearing assembly to define a lubricant reservoir enclosing said assembly, said reservoir wall terminating in an upper plane above the contact zone between said bearing block and shoe, whereby the shiftable surfaces of said bearing assembly may be fully submerged in lubricant retained in said reservoir, a removable cover for said reservoir formed with an opening arranged to shiftably receive said shoe, an upstanding marginal flange defining said opening, and a closure element fixedly carried by said shoe and formed with a depending flange cooperating in relatively shiftable telescoping relation with said upstanding flange to close said reservoir against entrance of foreign matter therein.
